UNITED STATES PATENT OFFICE.

JULES J. BRELL, OF NEW YORK, N. Y., ASSIGNOR OF ONE-FOURTH TO DAVID F. STERN
AND ONE-FOURTH TO PINCKNEY W. HAMILTON, BOTH OF NEW YORK, N. Y.

SCOURING DEVICE.

Application filed January 3, 1928. Serial No. 244,302.

This invention relates to a device used for scouring pots, pans, dishes, bottles or other household utensils and has for its object to provide an abrasive material and improved holder for the same, permitting such abrasive material to be easily held and economically used.

A further object of this invention is to provide an improved holder for abrasive polishing material and a novel way of packing the material in its holder, whereby such material can be maintained in a convenient and uniform shape, despite hard use and will be so held that it cannot cut or mar the fingers while being used for polishing or other purposes.

This invention further relates to an improved means of packing metallic wool or other abrasive material in a holder of the character disclosed in my co-pending application, Serial No. 214,835 filed August 23, 1927. The manner in which the metallic wool is held in its sectional separable container is such that strands or fibers of the wool cannot be readily separated from the bundle or pack held in the casing or cover.

With these objects and such other objects as may hereinafter appear, in view, I have devised the particular arrangement of parts hereinafter set forth and more particularly pointed out in the claims appended hereto.

Reference is to be had to the accompanying drawing in which

Figure 1 is a front elevation of my improved scouring or polishing device;

Figure 2 is a vertical sectional elevation of the same;

Figure 3 is a sectional view on the line 3-3 of Figure 2 looking in the direction of the arrows;

Figure 4 is a side elevation of the bundle of abrasive material or metallic wool indicating the manner in which the same is doubled upon itself for insertion into the tubular cover or the casing;

Figure 5 is an enlarged view of a few of the strands which compose the bundle of metallic wool abrasive;

Figure 6 is a plan view of a modified form of stiffening block;

Figure 7 is a sectional view on the line 7-7 of Figure 6, looking in the direction of the arrows, and

Figure 8 is a vertical sectional view of a portion of a scouring device in which a block

such as is disclosed in Figures 6 and 7 is used.

Throughout the various views of the drawings, similar reference characters designate similar parts.

In the embodiment of my invention disclosed in Figures 1 to 5 inclusive of the accompanying drawing, 1 indicates the tubular casing that is used for containing a metallic wool abrasive 2. The casing may be of any suitable material which possesses sufficient stiffness to hold its shape, yet which will possess a desired resiliency to enable it to grip its contents firmly and maintain the entire package in a substantially cylindrical form. The material from which the casing may be made should preferably be waterproof or water-repellant and I have found moulded rubber or a material composed in part of rubber particularly useful in making said casing. Assuming therefore, that the casing 1 is composed of moulded rubber or some similar material, said casing is provided with a plurality of spaced grooves 3 which divide the casing into a number of ribs 4 located intermediate of the grooves.

At 5 is shown a series of punched-out tabs which are so arranged that they may be successively raised and pulled with the result that successive sections of the casing will be severed or torn off from the casing to expose parts of the wool abrasive 2 as fast as the same is worn away in use. One end of the casing is preferably closed by a stiffening member or block 10 which may be made of wood, metal, fiber or of any substantially solid or rigid material and this block acts to maintain the shape of the casing 1 and enables the casing to be securely grasped and firmly held while the device is being used. Said block 10 is preferably provided with a central opening or hole 11 to permit drainage and ventilation for the metallic wool abrasive 2. If desired, there may be a series of openings in the block to facilitate drainage to such an extent as may be required. Thus, when the device is placed upright, there is a tendency for such water as may gather in the metallic wool abrasive 2 to pass out through the opening 11 or through as many openings as may be placed in the block 10, thus effectively draining the metallic wool 2.

The metallic wool 2 preferably consists of

a series of long fibers 12, a plurality of these fibers being twisted together as is shown in Figure 5 to form strands 13. A bunch of strands thus formed, of suitable length, are placed together as disclosed in Figure 4 and the bunch is doubled or folded over as at 14^a, the double bunch being forced into the casing 1. When in this position, the casing securely holds the strands or fibers and the fibers thus extend parallel to the axis of the casing. The doubled bunch of strands or fibers is securely held in position within the casing by crossed staples 14 and 15 which pass through the casing 1 and have inwardly bent prongs 6 that project into the sides of the block 10. It will be seen that the staple 15 passes through the loop in the bend or fold 14 of the folded bunch of metallic wool fibers and holds it securely in position. The other staple 14 passes at right angles to the staple 15 and passes between the fibers as is clearly disclosed in Figure 2.

If desired, the various fibers need not be twisted to form the separate strands as shown in Figures 2 and 5, this being desirable however, as it tends to hold the fibers securely together as well as rendering manufacture of the bunch of fibers easily performed.

30 It will be seen that the manner in which the steel wool is produced retains the fibers longitudinally in the casing and prevents long fibers from being displaced or readily pulled out, as the same are securely bound under the staples 14 and 15 and particularly under the staple 15. On the other hand, this disposition of the metallic wool abrasive permits the fibers to be readily broken or worn off as the article is used, constantly producing a new cutting or abrasive surface for the wool. It is also found desirable in some cases where the device produced is intended to have an extremely long and continuous use, to utilize some means of preventing oxidization or rusting of the fibers. This can be had by applying an oily rust-proofing compound to either the fibers 12 or the twisted strands 13 or by giving either these fibers, strands or the entire bunch of fibers 2 some other rust-proofing treatment.

55 The manner in which the bunch of metallic wool abrasive 2 is put in place avoids loosening of the strands as the device is used but instead enables the same to be held securely at all times and permits a gradual wearing away of the same, constantly exposing new cutting ends on the fibers as wearing occurs.

60 From the foregoing, the manner in which my improved scouring device is used will be readily understood. The device is merely held in the hand and the metallic wool

which projects from the open end of the casing 1 may be vigorously rubbed on pots, pans or other household implements. When 65 the projecting portion of the wool 2 becomes worn away by use, a new part is exposed by raising one of the tabs 5 and by pulling it off so that a section of the casing is torn away on the line of the groves 3 located 70 adjacent to the tab that is pulled. The exposed part of the wool is then used until it again becomes worn away whereupon the procedure just described is repeated.

In Figures 6, 7 and 8 is shown a modified 75 form of stiffening block. Here the block 16 is provided with the conventional central drain opening 11 which passes through a reduced portion 17.

The formation of this reduced portion 80 produces a shoulder 18. A plurality of small drain openings 19 extend through the block and terminate at the shoulder 18.

Through the construction just described, the scouring device may be rested upright 85 upon a support as at 25 and stood upon the reduced portion 17. When placed in that standing position, it will be seen that the drain holes 19 remain unobstructed and permit the free drainage of water that may 90 have accumulated in the wool bundle 2.

If desired, the under surface of the block 16 may be made concave as at 20 to enable the fold in the wool bundle 2 to more readily shape itself to the curvature of the 95 block. This concavity also aids in directing drain water towards the drain openings 11 and 19.

Having described one embodiment of my invention, it is obvious that the same is not 100 to be restricted thereto but is broad enough to cover all structures coming within the scope of the annexed claims.

What I claim is:

1. A scouring device consisting of a plurality of elongated metallic wool fibers 105 twisted to form a series of separate strands, a multiplicity of said twisted strands being held together to form a doubled over bundle, a severable tubular casing for receiving said bundle, and means for holding said doubled-over bundle within the casing so that the ends of said fibers forming said bundle protrude out of one end of said casing.

2. A scouring device consisting of a casing, steel wool held therein, a block fitted in one end of said casing, a shoulder on said block, and a plurality of drain openings 115 passing through the block and terminating at the shoulder thereon.

Signed at the city, county and State of New York, this 31st day of December, 1927.

JULES J. BRELL.
